(57) **CLAIM**

The ornamental design for a lever-actuated suction cup, as shown and described.

DESCRIPTION

FIG. 1 is a perspective view of a lever-actuated suction cup in accordance with my design, prior to actuation of the lever; FIG. 2 is a top plan view of the lever-actuated suction cup with the lever in the orientation shown in FIG. 1;

FIG. 3 is a front elevational view of the lever-actuated suction cup with the lever in the orientation shown in FIG. 1;

FIG. 4 is a right side elevational view of the lever-actuated suction cup with the lever in the orientation shown in FIG. 1, and with the left side elevational view being a mirror image;

FIG. 5 is a rear elevational view of the lever-actuated suction cup with the lever in the orientation shown in FIG. 1;

FIG. 6 is bottom plan view of the lever-actuated suction cup with the lever in the orientation shown in FIG. 1

FIG. 7 is a perspective view of the lever-actuated suction cup of FIGS. 1-6, after actuation of the lever;

FIG. 8 is a top plan view of the lever-actuated suction cup with the lever in the orientation shown in FIG. 7;

FIG. 9 is a front elevational view of the lever-actuated suction cup with the lever in the orientation shown in FIG. 7;

FIG. 10 is a right side elevational view of the lever-actuated suction cup with the lever in the orientation shown in FIG. 7, and with the left side elevational view being a mirror image;

FIG. 11 is a rear elevational view of the lever-actuated suction cup with the lever in the orientation shown in FIG. 7; and,

FIG. 12 is bottom plan view of the lever-actuated suction cup with the lever in the orientation shown in FIG. 7.
